(57) **CLAIM**

The ornamental design for an attachable cuff, as shown and described.

DESCRIPTION

FIG. 1 is a perspective view of an attachable cuff in a closed position showing my new design;

FIG. 2 is a perspective view showing the attachable cuff in an opened position thereof;

FIG. 3 is a top plan view thereof;

FIG. 4 is a bottom plan view thereof;

FIG. 5 is a front side elevational view thereof;

FIG. 6 is a rear side elevational view thereof;

FIG. 7 is a left side elevational view thereof; and,

FIG. 8 is a right side elevational view thereof.

The broken lines shown on the figures are for illustrative purposes only and are hereby disclaimed as forming no part of Applicant's claimed invention.
